GRIDDLE

Ollyn A. Layne, South Pasadena, Calif.

Application July 2, 1948, Serial No. 147,346

Term of patent 14 years

(Cl. D44—1)

To all whom it may concern:

Be it known that I, Ollyn A. Layne, a citizen of the United States, residing at South Pasadena, in the county of Los Angeles and State of California, have invented a new, original, and ornamental Design for a Griddle, of which the following is a specification, reference being had to the accompanying drawing, forming part thereof.

Fig. 1 is a perspective view of a griddle showing my new design; and

Fig. 2 is a sectional view thereof taken on line 2—2 of Fig. 1.

I claim:

The ornamental design for a griddle, as shown.

OLLYN A. LAYNE.
